UNITED STATES PATENT OFFICE.

WILSON S. ROUSH, OF WORTHINGTON, OHIO, ASSIGNOR OF ONE-HALF
TO WILLIAM ROUSH, OF MOUNDSVILLE, WEST VIRGINIA.

RAIL-TIE.

SPECIFICATION forming part of Letters Patent No. 788,602, dated May 2, 1905.

Application filed July 8, 1904. Serial No. 215,797.

To all whom it may concern:

Be it known that I, WILSON S. ROUSH, a citizen of the United States, residing at Worthington, in the county of Franklin and State of Ohio, have invented new and useful Improvements in Rail-Ties, of which the following is a specification.

This invention relates to a metallic railway-tie; and the primary object of the same is to provide a comparatively simple device of this class having structural features to positively coöperate with rail-clamps or holding devices which are substituted for and advantageously replace spikes ordinarily employed in securing rails to wooden ties to expedite railway construction and obstruct loosening of the rails, but permit expansion and contraction of the same under changes of temperature.

A further object of the invention is to provide a tie having clamping or holding devices adjustable in relation thereto which may be readily operated to accommodate repairs or grading and of a strong and durable nature.

The improved tie consists of a metal body of elongated form having an upper dovetail seat or slot opening out through the top thereof in which the shanks of clamping or holding heads are slidably mounted and adapted to be held in engagement with rails by readily applicable and removable keys or wedges inserted transversely through the upper portion of the tie at regular intervals.

The invention further consists in the construction and arrangement of the several parts, which will be more fully hereinafter described and claimed.

In the drawings, Figure 1 is a top plan view of the improved tie, showing portions of rails disposed thereon. Fig. 2 is a side elevation of the tie broken away at one end, showing rails in section supported thereby. Fig. 3 is a transverse vertical section on the line 3-3, Fig. 1. Fig. 4 is a detail elevation of one of the clamps or holders.

Similar numerals of reference are employed to indicate corresponding parts in the several views.

The numeral 1 designates the improved tie, which is formed of suitable metal and has op-

positely-extending base-flanges 2 and an under concave edge 3 to render the flanges 2 effective in preventing the tie from slipping by permitting the earth on a track-bed to fill up or engage the lower concave edge, and thus obstruct any tendency of displacement of the ties in a direction longitudinally of the track. The tie also has a head 4 with an upwardly-opening dovetail slot 5 longitudinally therethrough from end to end, the portion 6 of the tie between the head and the flanges being reduced and providing opposite longitudinal recesses 7 to receive the ballast or filling for the track, which will serve as a further means for preventing movement of the ties.

Clamps or holders are removably and adjustably mounted in the tie, and each clamp embodies a shank 8 of the same contour in cross-section as the slot or seat 5, the widest part of each shank being at its lower edge to prevent the several shanks from rising and becoming disengaged from the head 4. At one end of each shank is an upwardly-extending head 9, which is of materially greater width than the shank and the slot 5 to provide an extended bearing or contacting surface for engagement with the base-flange 10 of a rail 11. At an intermediate point each head is formed with an outwardly-opening throat 12, corresponding in contour to and adapted to receive the portion of the rail-flange 10 on opposite sides of the web of the rail, the throat being deep enough to permit the free end of the head 9 to snugly bear against the portion of the web of the rail immediately above said base-flange. Each tie is equipped with four of the clamps or holders, and the latter are all of substantially the same construction as those engaging the outer portions of the rails, which have key-slots 13, extending transversely therethrough close to the heads.

The clamps or holders are inserted in the slot 5 from opposite ends of the tie, with the heads of the inner clamps located outwardly and the heads of the outer clamps projected inwardly. Primarily, the clamps or holders are separated far enough to permit the rails 11 to be inserted between the opposing heads, and after the rails have been properly posi-

tioned the clamps are moved toward the rails and the flanges of the latter enter the throats 12. To hold the clamps against movement after they have been adjusted to engage the 5 base-flanges of the rails, wedge-plates 14 are inserted through slots 15, extending transversely through the head 4 of the tie and the slots 13 in the shanks of the outer clamps, which coincide with the said slots 15 when 10 the said outer clamps are properly adjusted against the rails. The wedge-plates 14 are formed with recesses 16 at their inner edges of such length as to permit the plates to be pushed inwardly and embrace the opposite 15 portions of the head 4 adjacent to the slots 15. After the plates 14 are thus disposed wedge-shaped keys 17 are inserted through the slots 13 and 15 against the outer edges of the plates 14, and accidental separation of said 20 keys from the head 4 and shanks 8 is prevented by cotter-pins or analogous devices 18, inserted through the reduced extremities thereof. The inner clamps are shoved outwardly to cause their heads to engage the inner portions of the base-flanges of the rails, and a wedge-plate 18' is then inserted through 25 an opening 19, extending transversely through the center of the head 4, the plate 18' being of the same contour and construction as the plates 14 heretofore described. After the 30 wedge-plate 18' is inserted through the slot or opening 19 it is pushed up against the inner end of one of the shanks 8 to lock it against accidental disengagement through the 35 medium of a central recess 20 in one edge thereof similar to the recesses 16 in the plates 14, and a wedge-shaped key 21 is then inserted through the slot or opening 19 and bears closely against the edge of the plate 18', 40 opposite that having the recess 20 therein, and also against the inner end of the shank 8 of the remaining clamp located between the rails. A cotter-pin or analogous device 22 is then inserted through the reduced extremity 45 of the key 21. The edges of the plates 14

and 18' and keys 17 and 21 which engage are inclined in reverse directions for obvious reasons, and the edges of the keys which directly bear against the outer terminals of the slots 15 and the inner end of one of the clamp-shanks are straight, and hence the clamping members are firmly held against movement, but may be quickly adjusted to disengage the heads thereof from the rail-flanges by withdrawing the keys 17 and 21 and shifting the 55 plates 14 and 18'.

The improved tie will be found exceptionally economical in that it will not be subject to decay, and track repair will be reduced to a minimum, especially in view of the absence 60 of spikes and the substitution therefor of the clamping members. Furthermore, the rails will be held uniformly level and prevented from sinking. Changes in the proportions, dimensions, and minor details may be resorted 65 to without departing from the spirit of the invention.

Having thus fully described the invention, what is claimed as new is—

A rail-tie having a dovetail slot extending 70 longitudinally through the upper portion thereof and opening out at opposite ends, clamps having shanks similar in form to the slot and slidably mounted in the latter, said clamps also having heads at one end which 75 project above the upper edge of the tie and are adapted to engage the base-flanges of rails, wedge-plates transversely inserted through slots in the tie and shank and having recessed edges to embrace the opposite sides of the tie, 80 wedge-keys also inserted through said slots and holding said clamping-plates, and means for securing the keys against withdrawal.

In testimony whereof I affix my signature in presence of two witnesses.

WILSON S. ROUSH.
